CLAIM

The ornamental design for a clothespin, as shown and described.

DESCRIPTION

FIG. 1 is a top plan view of a clothespin showing my new design;

FIG. 2 is a side elevational view thereof;

FIG. 3 is an end elevational view as seen from the left of FIG. 1;

FIG. 4 is an elevational view of the opposite end thereof; and

FIG. 5 is a perspective view thereof.

*Fig. 1.**Fig. 2.**Fig. 3.**Fig. 4.**Fig. 5.*
